UNITED STATES PATENT OFFICE.

GEORGE M. DEWAR, OF INDIANAPOLIS, INDIANA, ASSIGNOR OF ONE-HALF TO
ALBERT THOMPSON, OF INDIANAPOLIS, INDIANA.

LAMP SOCKET AND SHADE HOLDER.

1,092,810.

Specification of Letters Patent.

Patented Apr. 7, 1914.

Application filed August 11, 1913. Serial No. 784,099.

To all whom it may concern:

Be it known that I, GEORGE M. DEWAR, a citizen of the United States, residing at Indianapolis, in the county of Marion and State of Indiana, have invented a new and useful Lamp Socket and Shade Holder, of which the following is a specification, reference being had to the accompanying drawings and to the letters and figures of reference marked thereon.

This invention relates to an appliance for detachably connecting electric lamps to the required circuit wires, the invention relating also to means for holding a lamp shade; the invention having reference more particularly to lamp sockets of the type that is provided with a switch or circuit breaker.

An object of the invention is to provide an improved appliance for electric lamps that shall be so constructed as to permit the switch box and the key connected therewith to be readily applied to or removed from the appliance, a further object being to provide a simply constructed and relatively cheap lamp appliance which shall be relatively light in weight and stiff and adapted to be connected either to a pipe or to be suspended by a chain or cord.

A still further object of the invention is to provide a lamp socket and shade holder appliance or socket cover that may be formed as a unitary element, so as to be cheaply formed and be strong and durable in use.

With the above mentioned and other objects in view, the invention consists in certain novel features of construction in electric lamp sockets and shade holders, and in the parts and combinations and arrangement of parts as hereinafter particularly described and defined in the accompanying claims.

Referring to the drawings Figure 1 is a front elevation of the improved lamp socket and shade holder as preferably constructed, portions of a lamp, a shade and a supporting pipe being shown in dotted lines in connection therewith; Fig. 2, a section on the line A—A in Fig. 1; Fig. 3, a section of the principal part of the improvement taken on a plane at right angles to the plane of the line A—A; Fig. 4, an inverted plan of the principal part of the improvement; Fig. 5, a central section of one of the parts of the improvement; Fig. 6, an inverted plan view of the parts shown in the preceding figure; Fig. 7 a fragmentary section of the

principal part shown as when partially completed.

Similar reference characters in the different figures of the drawings indicate corresponding elements or features of construction herein referred to.

In practically carrying out the objects of the invention the socket portion thereof preferably comprises a number of parts of which one part is formed as a truncated tube 1 composed of sheet metal, one end of the tube having an outwardly extending flange 2 thereon from which extends a skirt which may be variously shaped for ornamental purposes and preferably comprises a flaring portion 3 extending from the flange so as to encircle the tube, a cylindrical portion 4 extending from the portion 3 and from which a flaring portion 5 extends, a cylindrical portion 6 extending from the portion 5 to a plane beyond the opposite end of tube 1, the tube and the skirt preferably being spun from a single piece of metal, and the end of the portion 6 preferably is turned over to form a stiffening bead 7. Preferably the skirt or socket cover is formed of two layers so as to have double thickness of metal, that described being the inner portion or layer of the skirt, the outer portion or layer thereof comprising a cylindrical portion 8 extending from the bead about the portion 6 and preferably formed integrally with the bead, a portion 9 corresponding to the portion 5 extending from the portion 8, a portion 10 corresponding to portion 4 extending about the latter from the portion 9, a contracted portion 11 extending from the portion 10 on to the portion 3, a contracted portion 12 extending from the portion 11, an approximately cylindrical neck 13 extending from the portion 12, the neck being slightly larger in diameter than the tube 1 and having screw threads 14 formed on its end portion. The exterior of the skirt and neck is approximately bell-shaped, and the neck has a slot 15 extending from the end or top thereof when a switch is used adjacent to the socket, or may be omitted when the lamp is provided with a switch or circuit breaker at a considerable distance from the lamp. The inner and outer portions of the skirt may be slightly separated during formation as in Fig. 7 but are brought closely together when finished. Suitable devices are provided to

enable the skirt to hold a lamp shade; three screw-threaded bushings 16, 17 and 18 preferably being fixed in suitable openings therein and receiving set-screws 19, 20 and 21 respectively for engaging the neck of the shade. A dome shaped crown 22 is provided, preferably of sheet metal, and its edge portion is provided with screw threads 23 adapted to screw on to the threads 14, so as to not accidentally become disconnected therefrom, the crown partially covering the slot 15 when in proper position. The top or middle portion of the crown is provided with a collar 24 preferably having screw threads 25 therein for connection with a supporting pipe that commonly incloses the circuit wires for the lamp, a set-screw 26 preferably being inserted in the collar for securing the latter to the pipe. Preferably the collar has sockets 27 and 28 in opposite portions thereof in order that the collar may be provided with a supporting ring or loop 29 that has lugs 30 and 31 adapted to be inserted into the sockets, in case the collar is not connected to the pipe and it is desired to suspend it by means of a chain or cord.

In accordance with common practice a tubular insulating lining 32 is placed within the tube 1 and extends through it into the neck 13, the upper portion of the lining preferably being slightly greater in diameter than that within the tube and having a bearing upon the flange portion 2. A switch box or plug 33 is placed within the neck portion of the lining and may suitably be composed of porcelain, and it has a socket member 34 secured thereto that is provided with screw threads 35 to which the electric lamp shank is directly connected, so as to form an electric circuit therewith and in connection with a contact point 36 with which the switch box is provided as usual, a shaft 37 being rotatably mounted in the switch box and having a key shank 38 thereon that extends through the slot 15 and is provided on its outer end with a handle or lever 39. The circuit wires 40 are brought through the collar 24 and connected with suitable binding posts in the switch box that are connected with a contact device 41 adapted to be engaged by a switch arm 42 mounted on the shaft 37, the switch arm being moved into contact with a plate on which the contact point 36 is formed to close the circuit, as will be understood.

When assembling the various elements of the invention the circuit wires are passed through the collar 24 and properly connected with the switch box, and the latter and the socket member 34 are inserted in the insulating lining 32, after which the lining is inserted into the tube 1 which constitutes a casing for the insulation; the shank or stem 38 being readily moved into the slot 15 of neck 13 which constitutes a casing for the

switch box, after which the crown or cover 22 is screwed onto the neck or otherwise detachably secured to the neck, as may be desired.

In practical use the electric lamp is 70 screwed into the socket member 34 as is customary, and the lamp shade is inserted into the skirt or ring that extends about the socket and is removably held by the set-screws 19, 20 and 21. The circuit is made 75 or broken in the usual manner.

Having thus described the invention, what is claimed as new is—

1. A lamp socket and shade holder appliance including a socket tube, and a skirt comprising an inner portion and an outer portion formed integrally with one end of the inner portion, the opposite end of the inner portion being integrally connected to one end of the tube, the outer portion extending from the end of the inner portion about and beyond the inner portion. 80 85

2. A lamp socket and shade holder including a truncated tube, a skirt comprising an inner portion and an inclosing outer portion secured together and extending about the tube, the inner portion of the skirt being connected to the tube, the outer portion of the skirt having a neck thereon extending beyond the inner portion thereof, and a 90 95 crown removably secured to the end of the neck.

3. A lamp socket and shade holder appliance including a unitary structure comprising a truncated tube and a skirt extending integrally from one end of the tube and outwardly about the tube, the skirt having a neck thereon extending beyond the plane of the end of the tube, the tube being provided with means for holding a lamp, the skirt 100 105 being provided with means for holding a shade, and a crown detachably secured to the end of the neck.

4. A lamp socket and shade holder appliance including a truncated tube and a 110 skirt connected together and provided with a neck common to both, the skirt extending about the tube, the neck having a slot extending from the end thereof, a switch box seated in the neck, a switch key connected 115 with the switch box and extending through the slot, and a crown detachably secured to the neck and partially covering the slot.

5. A lamp socket and shade holder including a skirt comprising an inner portion and an outer portion extending about the inner portion and having a neck thereon provided with a connecting device, the inner portion of the skirt having a tubular socket portion connected thereto, screw-threaded 120 125 bushings inserted in the inner and outer portions of the skirt, set-screws inserted in the bushings respectively, and a crown having a connecting device detachably connected with the connecting device of the neck. 130

6. A lamp socket and shade holder including a tube, a skirt connected to the tube, a neck connected to the skirt and provided with screw threads, a crown provided with 5 screw threads connected with the threads of the neck, a collar connected to the crown and having sockets therein, a ring having lugs inserted in the sockets, a plug in the neck, a screw threaded socket member in the 10 tube connected to the plug, insulating lining extending between the tube and the socket member and between the neck and the plug, and circuit wires extending through the collar to the plug.
- 15 7. A lamp socket and shade holder including a socket tube, an inner skirt portion formed integrally with the inner end of the tube and extending flaringly therefrom, an

outer skirt portion formed integrally with the outer or larger end of the inner skirt portion and extending closely about the inner portion, the outer skirt portion having a neck thereon beyond the plane of the inner end of the tube, a plug in the neck, a screw threaded socket member in the tube connected to the plug, insulating lining extending between the tube and the socket member and between the neck and the plug, and a crown detachably secured to the neck.

In testimony whereof, I affix my signature 30 in presence of two witnesses.
